UNITED STATES PATENT OFFICE.

WILLIAM H. HARRISON, OF CENTRE HILL, ARKANSAS.

BEDSTEAD.

SPECIFICATION forming part of Letters Patent No. 508,517, dated November 14, 1893.

Application filed February 14, 1893. Serial No. 462,325. (No model.)

To all whom it may concern:

Be it known that I, WILLIAM H. HARRISON, a citizen of the United States, residing at Centre Hill, in the county of White and State of 5 Arkansas, have invented a new and useful Bedstead, of which the following is a specification.

This invention relates to bedsteads, and has special reference to means for supporting 10 the slats in a simple and convenient manner, and has for its object to provide for a quick attachment or detachment of the slats with a material decrease in the cost of forming the parts of the bed, and with the additional advantage of dispensing with crevices and angles 15 and avoid the lodgment of vermin thereon; and with this end in view, the invention consists of the construction and arrangement of the parts thereof as will be more fully here- 20 inafter described and claimed.

In the drawings: Figure 1 is a perspective view of a bedstead embodying the invention. Fig. 2 is a similar view of one of the side-rails 25 of the bedstead, showing portions of the slats slightly above the same and disconnected therefrom. Fig. 3 is a perspective view of one of the slats. Fig. 4 is a similar view, in detail, of the catch used in connection with the opposite ends of the slats.

Similar numerals of reference indicate corresponding parts in the several figures of the drawings.

Referring to the drawings, the numeral 1 designates the oppositely-situated side-rails 35 of the bedstead, which are secured or attached to the head and foot boards in any preferred and well-known manner. In this construction and arrangement, the side-rails are perfectly plain on their inner opposing 40 sides and do not have supporting shoulders or recesses therein, thereby materially cheapening their construction, as will be evident. In this device the inner opposing sides of the rails are similarly constructed, as are also the 45 opposite ends of the slats, and in referring to the same one rail only will be described, together with the adjacent engaging ends of the slats.

To the inner side of the rail, adjacent to the

bottom edge of the same, is secured a round 50 wire or rod 2, that extends longitudinally thereof from end to end of the same, and held in connection therewith by a series of staples 3, that are driven thereover at predetermined distances and are regularly spaced 55 apart in pairs to form stops for a purpose which will presently appear. The application of the round wire or rod 2 to the inner side of the rail 1 tends to provide an increased 60 rigidity to the said rail, and prevents the same from sagging or warping in a vertical plane, or from bulging outwardly or inwardly, and thereby always holds the said rail in a straight position. As previously stated, the 65 inner side of the rail is not formed with the usual shoulder and recesses, but in the present construction, just inside of each pair of staples 3, a pair of recesses 4 are formed that extend in a vertical plane and are arranged 70 in this manner because the round wire or rod 2 is closely held against the rail, and it would be necessary to slightly recess the rail in rear of the said wire or rod, toward the outside portion of the rail, in order to form a means 75 of attaching the slats. The slats 5, in this instance, are of the ordinary form of construction, and their opposite ends are brought to bear firmly against the inner opposing sides of rails. Attached to the under side, 80 adjacent to each end of each slat, is a catch consisting of a U-shaped wire or rod 6, having its free ends bent downwardly to form hooks 7, that project slightly beyond the end 85 of the slat. The said catch is secured to the under side of the slat by a series of staples 8, that embrace the two legs thereof and also the bow or bend of the same, and by this means it is held firmly in position against the slat and in its normal adjustment. In attaching the slats to the rail at either side, the 90 hooks 7 of the catches are inserted in the recesses 4, outside of the round wire or rod 2, and thereby the end of each slat is closely drawn and firmly abuts against the inner side of the rail. The staples 3 are engaged 95 by the said hooks 7, and prevent longitudinal or loose movement of the slat-ends and provide a firm connection for the same.

It will be understood that in attaching the slats to the rails in the manner set forth, that the opposite ends of said slats may be unitedly connected and readily withdrawn by 5 raising the same vertically.

Labor and time are saved in the manufacture of a bedstead when constructed in accordance with the invention heretofore set forth, and the cost materially reduced, and 10 at the same time convenient and advantageous means are provided for attaching the slats in position.

By having the opposite ends of the slats drawn closely against and held against the inner opposing sides of the opposite rails, the parts of the bedstead are prevented from becoming distorted or misshaped when the same is moved, and especially after the joints may have become slightly loose by wear or 15 shrinkage, and strain on the connections or fastenings between the rails and head and foot boards is obviated, and also injury to the slat-fastenings set forth will not occur. It will be seen that if the slat-ends did not 20 closely abut against the inner sides of the rails the space for movement of the rails would be provided, and when the bedstead was moved it would twist, owing to its weight, and assume a rhomboidal shape, which would 25 wear upon the joints and also strain the rails and crack or break the same. A further advantage of the close fitting of the ends of the slats relatively to the rails is that the said slat-ends cannot become readily detached; 30 and further, by means of the arrangement of the pairs of staples, no lateral movement of

the ends of the slats in a longitudinal direction of the rails cannot occur.

Having described the invention, what is claimed as new is—

In a bedstead, the combination of the rails having round wires or rods secured closely against and to the inner opposing sides thereof near the lower edges of the same by staples spaced apart at predetermined intervals 45 in pairs, said rails being formed with recesses that are also arranged in pairs which are located adjacent to and inside of the pairs of staples, said wires or rods extending longitudinally of the rails from end to end 50 thereof, and slats having catches secured to the under side of the opposite ends thereof, consisting of U-shaped wires or rods with outer downwardly-bent ends to form hooks that project beyond the opposite ends of the 55 slats and are adapted to take over the said wires or rods and fit in the recesses in the rails, said hooks being confined between and bearing against the inner sides of said pairs of staples and drawing the ends of the slats 60 closely against the inner sides of the rails, whereby distortion of the bedstead is prevented in moving the same and strain on the several connecting parts and joints obviated, substantially as described. 55

In testimony that I claim the foregoing as my own I have hereto affixed my signature in the presence of two witnesses.

WILLIAM H. HARRISON.
